(57) **CLAIM**

The ornamental design for an architectural shape, as shown and described.

DESCRIPTION

FIG. 1 is an isometric view of the architectural shape of my new design.

FIG. 2 is a front elevational view of my new design. The back elevational view is identical.

FIG. 3 is a left side elevational view of my new design.

FIG. 4 is a right side elevational view of my new design.

FIG. 5 is a top plan view of my new design; and,

FIG. 6 is a bottom plan view of my new design.
